UNITED STATES PATENT OFFICE.

ERNEST WILLARD CRANE, OF BUENA VISTA, FLORIDA, ASSIGNOR OF ONE-HALF TO
CHARLES H. COOPER, OF BUENA VISTA, FLORIDA.

LIQUID-CONVEYER.

1,303,814.

Specification of Letters Patent. Patented May 13, 1919.

Application filed June 5, 1917. Serial No. 172,956.

To all whom it may concern:

Be it known that I, ERNEST WILLARD CRANE, a citizen of the United States, residing at Buena Vista, in the county of Dade and State of Florida, have invented certain new and useful Improvements in Liquid-Conveyers; and I do hereby declare the following to be a full, clear, and exact description of the invention, such as will enable others skilled in the art to which it appertains to make and use the same.

The invention relates to a liquid conveyer. The object of the present invention is to provide a simple, practical and efficient device of strong, durable and inexpensive construction designed for conveying oil or other liquid from a barrel or other air-tight container to a non-air-tight receptacle by introducing air pressure into the barrel or container. A further object of the invention is to provide a device of this character which will be adapted to be easily and rapidly screwed into a bung hole and in which the discharge tube may be readily turned to discharge the liquid at the desired point.

With these and other objects in view, the invention consists in the construction and novel combination of parts hereinafter fully described, illustrated in the accompanying drawing and pointed out in the claim hereto appended; it being understood that various changes in the form, proportion, size and minor details of construction, within the scope of the claim, may be resorted to without departing from the spirit or sacrificing any of the advantages of the invention.

In the drawing:

Figure 1 is a side elevation partly in section of a liquid conveyer constructed in accordance with this invention.

Fig. 2 is an enlarged sectional view of the same.

Like numerals of reference designate corresponding parts in all the figures of the drawing.

In the accompanying drawing, in which is illustrated the preferred embodiment of the invention, the liquid conveyer comprises in its construction a tapered bung 1 having exterior screw threads 2 and adapted to be screwed into the bung hole 3 of a barrel 4, as clearly illustrated in Fig. 1 of the drawing. The bung 1 is provided at the top with a polygonal flange 5 adapted to receive

a wrench or other tool for screwing it into and out of the barrel or other container. 55

The bung 1, which may be constructed of any suitable material, is provided with a central opening or passage 6 for the discharge of the liquid, and the said opening is enlarged at the upper end to form a recess 7 for the reception of the lower end of a goose neck discharge tube 8. The goose neck discharge tube 8, which may be of any desired length and shape, is provided at the lower end with an annular flange 9 fitted upon the bottom of the recess 7 and secured therein by means of a threaded ring 10 which has a threaded engagement with the bung at 11 at the upper portion of the side 70 wall of the recess 7. 60

The bung is also provided in its lower end with a recess 12 receiving the upper end of an inner tube 13 provided with a flange 14 fitted against the top wall of the bottom recess and secured therein by a threaded ring 15 having a threaded connection at 16 with the lower portion of the side wall of the lower recess. By swiveling or connecting the upper discharge tube and the inner or lower tube 13 with the bung in this manner, the bung may be readily screwed into a barrel without rotating either of the said tubes and it may also be quickly removed from the said barrel or other container. Also the connection enables the outer goose neck tube to be readily turned in the desired direction. 75 80 85

The inner tube 13 is provided with a lower telescopic or adjustable section 17 which is adapted to extend to the bottom of a barrel or container, as shown. The adjustable telescopic section passes through a gasket 18 which is held in a union 19 threaded onto the lower end of the inner tube 13 at 90 95 20 and provided with an interior annular groove 21 for the reception of the gasket 18. The gasket 18 may, however, be mounted in any other desired manner and it adjustably holds the telescopic tube or section. 100 The bung may be provided with washers or gaskets if desired, and the outer end of the discharge tube 8 is provided with a valve or cut-off 22 for controlling the discharge of the liquid. 105

The bung is also provided with an air passage 23 having an enlarged threaded portion 24 at the upper end to receive a suit-

able pipe connection or coupling for connecting an air supply pipe 25 to the bung. Compressed air may be supplied to the barrel from any suitable compressor and it will 5 force the liquid out of the barrel into a suitable receptacle 26 and the discharge of the liquid may be controlled by the cut-off 22. The air pressure is retained in the barrel or 10 other container until the liquid is expelled from the same, by means of a suitable check valve 27 located in the air supply pipe 25 or in the air passage 23. This check valve is of any desired construction, and as any 15 form of check valve may be employed a detail illustration of the same is deemed unnecessary.

What is claimed is:

A liquid conveyer of the class described including a bung adapted to be secured in

a bung hole and provided with a liquid passage enlarged at the upper end to form a recess, a goose neck outer discharge pipe having a flange on the lower end thereof positioned in the recess, a locking ring threaded into the recess and arranged to 20 swivelly hold the goose neck in position, a valve carried by the outer end of the goose neck, an intake tube carried by the lower 25 end of the bung, and means carried by the bung for admitting fluid pressure to the interior of the barrel for forcing the liquid out through tubes and liquid passage.

In testimony whereof I affix my signature in presence of two witnesses.

ERNEST WILLARD CRANE.
